METHOD OF TREATING WELLS

Gustaf E. Ostrom, Whittier, Calif., assignor to
 Mabel E. Richart, Fullerton, Calif., and Jack C.
 Renfro, Orange County, Calif.

Application June 14, 1938, Serial No. 213,598

3 Claims. (Cl. 166—21)

This invention relates to treatment of wells. The general object of the invention is to provide an improved method of treating a well, such for example as an oil well, to produce or to maintain or initiate a free flow of oil.

A more specific object of the invention is to provide an improved method of treating an oil well whereby the substances which clog the casing perforations or oil bearing formations are removed by a chemical reaction which takes place within the well and wherein the reaction occurs without injury to the equipment within the well.

A further object of the invention is to provide a novel method of treating an oil or other well to cause initial flow or to increase the flow wherein an acidizer which is solid at ordinary temperatures is lowered into the well in a suitable container there to react with water in the well and with other reagents to thereby liberate heat and gas and to produce solvents and dispersing media to react with and render removable the limestone, gum, paraffin waxes, rotary mud and such other material in the casing apertures or in the formation and which obstruct the flow of oil.

Another object of the invention is to provide a novel treatment of wells wherein a solid organic acid is introduced into the well.

Another object of the invention is to provide a novel method of treating wells wherein a halogenated solid organic acid is introduced into the well.

Another object of the invention is to provide a novel method of treating wells wherein an organic solid acid and a solid non-metallic halide is introduced into the well.

A further object of the invention is to provide a novel container for use in treating oil wells.

Other objects and advantages of the invention will be apparent from the following description taken in connection with the accompanying drawing, wherein:

Fig. 1 is a central sectional view showing an oil well under treatment according to my invention;

Fig. 2 is a central sectional view through a portion of the casing and one of the containers employed in practicing my invention;

Fig. 3 is a section taken on line 3—3 Fig. 2;

Fig. 4 is a section taken on line 4—4 Fig. 2; and

Fig. 5 is a fragmentary sectional view showing the closure cap in the container.

Referring to the drawing by reference characters I have shown my invention as employed in treating an oil well which is indicated generally at 10. The oil well includes a formation

11, with a casing 12 therein, the casing having slots 13 through which oil and gas pass to the interior of the casing and thence to the surface, either by free flow or by a pumping operation.

5 According to the invention I employ a string of units or cartridges 14 in which chemical changes take place and which units are lowered into the casing or into the well hole, if no casing is employed, by means of the sand line.

10 As shown each of the cartridges 14 includes a shell or tube 15 which is preferably made of steel and which is provided with internal threads 16 at the lower end and 17 at the upper end. In the lower end I arrange a threaded plug 18 which is provided with a central aperture 19. Apertures 20 afford communication through the plug 18 from the aperture 19 to the exterior. The lower end of the aperture 19 includes a reduced portion 21 in which I arrange a tube 22 which may constitute one of the reagents used in connection with my invention.

15 At its upper end the threads 17 on the tube engage a plug 23 which has a central aperture 24 and a plurality of lateral apertures 25 which afford communication between the aperture 24 and the exterior of the cartridge.

20 The tube 22 extends into the aperture 24 and is spaced from the wall of the aperture.

25 In shipment the exterior of the cartridge including the shell 14 and the plugs 18 and 23 are coated with grease as at 26. The grease enters the apertures 20 and 25 as shown at 27 in Fig. 5 to thus seal these apertures. A cap 28 is slipped over the plugs and extends down over the lateral apertures. This cap is slightly larger in diameter than the plug on which it is fitted. Each cap is 30 preferably provided with a bevelled interior portion 29 to provide a grease filled chamber 30. A screen 30' is provided at the lower end of the shell 14.

35 In use the cartridge, after arriving at the place of use, is prepared by removing the caps 28 which are threadedly held in place and by substituting threaded caps 31 which include apertures 32 through which a flexible cable 33 extends. The inner ends of the cable 33 include heads 34 which are disposed in the caps 31. In this manner a 40 string of the cartridges may be connected together and secured to the sand line. The lower cap 31 of the lower unit 14 does not have a cable aperture therethrough and neither does the upper cap of the upper unit 14 which is provided with a suitable bale for securing it to a sand line.

45 50 55 In the practice of my improved method I place

a solid organic acid of the type which is represented by acids such as chloroacetic acid, trichloroacetic acid, in granular form in the cylinder 14. The tube 22 is preferably made of magnesium. If desired I may also place in the cylinder 14 containers 35 which may be made of magnesium having the interior surface thereof coated with paraffin as at 36. These containers 35 preferably contain a non-metallic halide and may contain, for instance, phosphorus pentachloride.

After the cartridge is prepared and placed in the well the heat melts the grease at 27 so that water enters the lower apertures 20. The magnesium of the rod 22 reacts with the acid and the water reacts with the phosphorus pentachloride and also further reactions with the materials previously mentioned as disposed in the containers 35, or with the limestone or other materials in the well, occur. The products resulting from the reaction pass through the apertures 25.

The limestone is dissolved with evolution of carbon dioxide. Paraffin, wax, etc., are first melted, then dispersed colloidal by the excess acid used. Rotary mud is colloidal and the acidizers coagulate or precipitate this mud making it granular and removable.

The amount of material and the proportion of material used depends upon conditions within the well. As a typical straight acid treatment I may employ fifteen parts by weight of acid to one part magnesium. Another treatment may include 20 parts by weight of acid, 1 part of magnesium and 1 part of calcium carbide in which the calcium carbide would furnish a source of acetylene. A further typical acid treatment using acidizers with magnesium would employ 15 parts of acid to 1 part of magnesium and $\frac{1}{4}$ part of non-metallic halide.

The chemical changes within the units are started by water in the well, and depend on this water for satisfactory continuance. At the end of the treatment the string of units is pulled out of the hole. Any chemical effect on the casing can then be ascertained by the effect on the units since they are made of casing metal.

As a result of the vigorous exothermal chemical changes within the units, a large amount of heat is generated sufficient to raise the temperature of the hole fluids a hundred or more degrees. This softens and liquefies the waxy paraffin and asphaltic substances which clog the perforations or form obstructions on the walls or on the oil bearing formation.

The chemicals which are used in the units exert a powerful solvent or emulsifying effect on the materials which cause the trouble. It is rarely necessary to completely dissolve these but it is absolutely essential that they be dispersed into such a stable state of aggregation that they do not again coalesce and can be readily removed from the well.

Each well is a specific problem. After study and diagnosis of each well the nature and proportions of the chemicals in the units, the length of treatment, etc., are all so adjusted that maximum benefits result.

As products of the exothermic reactions within the units gases are evolved in considerable volume. These gases are projected in swift jets against the walls of the well and directly into the perforations or formation where they serve to agitate and remove the softened materials. The composition of the gas produced varies with the requirements in each case. Gas does not only serve to produce violent agitation but with the aid of the high hydrostatic pressure in the hole goes into solution to a considerable extent. The dissolved gas diffuses rapidly in its solvents and penetrates the oil bearing formation surrounding the perforations to substantially reduce the surface tension and viscosity of the material occluding the interstices through which the oil must pass in order to get into the well.

The whole system of units is moved up and down in the well by means of the sand line. This effective mechanical agitation serves to aid in disintegrating the materials.

From the foregoing description it will be apparent that I have invented a novel apparatus and method for treating an oil well which is highly efficient for the intended purpose.

Having thus described my invention I claim:

1. The method of initiating production or increasing the output of a well which comprises introducing into the well solid mono-chloracetic acid and phosphorus pentachloride.

2. The method of initiating production or increasing the output of a well which comprises introducing into the well mono-chloracetic acid together with magnesium and phosphorus pentachloride.

3. The method of initiating production or increasing the output of a well which comprises introducing into the well mono-chloracetic acid and magnesium.

GUSTAF E. OSTROM.
